UNITED STATES PATENT OFFICE.

GUILFORD S. MORLEY, OF UNIVERSITY CITY, MISSOURI, ASSIGNOR TO MAJESTIC MANUFACTURING COMPANY, OF ST. LOUIS, MISSOURI, A CORPORATION OF MISSOURI.

OVEN-DOOR REST.

Application filed October 24, 1927. Serial No. 228,111.

This invention relates to braces, or rests, and is illustrated herein as embodied in a rest of a type suitable for use in connection with hinged doors, such, for example, as the 5 oven doors of ranges, and the like.

It is customary to mount oven doors for free pivotal movement about a horizontally extending axis and to provide rests, or other suitable means, for limiting the downward 10 movement of the door when it is opened. Heretofore the rests have been securely fastened to the front of the stove in such a manner that they cannot be displaced either accidentally, or intentionally without the use 15 of tools, and, while they perform their intended function satisfactorily when so secured, it is evident that it would be extremely difficult to clean the rests properly while they are attached to the stove, or to clean the 20 portions of the stove located in the rear of the rests.

With the foregoing considerations in view the present invention has for an important 25 object thereof the provision of improved door rests which may be easily and quickly removed from a stove to which they are attached. By means of such a provision the rests and the portions of the stove located in the rear of the rests may be cleaned readily 30 and efficiently. As shown in the illustrative embodiment of the invention each of the rests is provided with an enlarged head adapted to fit slidably within a groove formed along one side of the oven door, and 35 with an arm having a perforation therein for receiving a hook-shaped saddle finger secured to the stove beneath the oven door. In removing the rests, they may conveniently 40 be raised to slide the enlarged heads along the slots formed in the door, and to move the perforated arms out of engagement with the saddle fingers. When the lower ends are thus lifted free of the saddle fingers, the rests may be rotated to move the enlarged heads 45 lengthwise within the grooves, from which position they may be readily extracted. When the rests have, in this manner, been removed from the stove, they may be cleaned and finally replaced with the same ease and 50 facility encountered in removing them.

Other features and objects of the invention will become apparent from a reading of the

following specification in the light of the accompanying drawings, in which:—

Fig. 1 is a view in front elevation showing 55 a stove provided with the novel rests;

Fig. 2 is a fragmentary view in side elevation of the device shown in Fig. 1; and,

Fig. 3 is a fragmentary view in front elevation of the device shown in Fig. 1, illustrating diagrammatically the manner in 60 which the rests may be removed from the stove.

As shown in the drawings, the reference 65 numeral 10 indicates the side walls, or framework, of a stove within which there is formed an oven. An oven door 12 for permitting access to the interior of the oven is pivoted at 14 for swinging movement about a horizontally extending axis from a 70 closed position to an open position, as shown in Fig. 2.

The stove is provided with rests for limiting the movement of the oven door, and to support the door when it occupies an open 75 position. As illustrated these rests, indicated at 16, are located at opposite edges of the door 12, and each of the rests is provided with a neck portion 18 terminating in an enlarged head, or projection, 20 and with a 80 lower, inwardly extending arm 24 formed therein. The ears or projections 20 of the rests 16 are adapted to slide in grooves 26 formed in the oven door, and the lower inwardly extending arms 22 are adapted to be seated within saddle members 28 secured to the frame of the stove below the door. Each saddle member 28 is provided with an upwardly extending finger 30 which is adapted 85 to pass through the opening 24 formed in the arm 22 of the rest. 90

From an inspection of Fig. 2 it will be seen that as the door moves from a closed to an open position the lower extremities of the rests pivot about the saddle 28 and the upper 95 portions of the rests slide within the grooves 26 until they come in contact with the wall at the end of the groove, thereby preventing further movement of the door in a downward direction and serving as a brace for 100 the door as long as it remains open.

The rests are mounted in such a manner that they may be readily removed from the stove in connection with which they are used,

and the manner in which the rests may be removed is clearly illustrated in Fig. 3. As there shown, the rests may be grasped manually and raised until the lower end, or the arm 5 22, is moved free and clear of the saddle 28 and finger 30, and thereafter the rests may be rotated through the position B, indicated in dotted lines, into the position A, also indicated in dotted lines. With the rests positioned as shown at A, it is obvious that the projection 20 is free to be extracted from the groove 26, and when such an extraction is effected it is apparent that the complete removal of the rest is obtained. In affixing 10 the rest to a stove the procedure just outlined is reversed, the projection 20 being inserted into the groove, the rest rotated and finally dropped down into locking engagement with the finger 30 of the saddle 28.

15 20 Having thus described my invention, what I claim as new and desire to secure by Letters Patent is:

1. In a device of the character described, a hinged door provided with an elongated 25 opening having a wall in which a slot is formed, said slot being of less width than said elongated opening, a rest to limit downward movement of said hinged door, a portion of said rest at one end thereof being extended 30 through said slot and disposed within said elongated opening, said portion of said rest within said elongated opening being incapable of passing through said slot when said rest is in its normal position, and said rest being 35 movable to bring said portion to a position where it will pass through said slot to disengage said rest from said hinged door, and a saddle mounted in a fixed position below the hinged door and adapted to removably support said rest.

40 2. In a device of the character described, a hinged door provided with an elongated

opening having a wall in which a slot is formed, said slot being of less width than said elongated opening, a rest to limit the downward movement of said hinged door, a portion of said rest at one end thereof being extended through said slot and disposed within said elongated opening with portions thereof overlapping edges of said slot, said end portion of said rest being loosely positioned within said elongated opening so that same may be turned therein to move said portion to a position where it may be passed through said slot to disengage said rest from said hinged door, and a saddle mounted in a fixed position below the hinged door and adapted to removably support said rest. 45 50 55

3. In a device of the character described, a hinged door provided with an elongated 60 opening having a wall in which a slot is formed, said slot being of less width than said elongated opening, a rest to limit downward movement of said hinged door, said rest at one end thereof being extended through 65 said slot and having a portion disposed within said elongated opening which portion is of greater length than the width of said slot, said portion of said rest within said elongated opening being of substantially less length 70 than the width of said elongated opening to permit turning thereof within said opening and being of such transverse dimension to permit passage thereof through said slot whereby said rest may be turned to position 75 at an approximate right angle to its normal position to disengage same from the hinged door, and a saddle mounted below the hinged door and adapted to removably support said rest. 80

In testimony that I claim the foregoing I hereunto affix my signature.

GUILFORD S. MORLEY.
